MANICURE INSTRUMENT

Edward L. Blackman, Greenwich, Conn.

Application November 26, 1946, Serial No. 712,370

9 Claims. (Cl. 132—74.5)

1

This invention relates primarily to manicuring and nail cleaning instruments and the like, but may be employed for the uses to which it is adaptable.

Heretofore many attempts have been made to provide a manicuring instrument which could be easily carried in the pocket and which would provide for the use of a liquid from a contained cleaner supply or reservoir. However, all of these instruments so far as is known have failed to provide a leakproof supply of liquid and an efficient instrument.

One object of this invention is to provide a portable instrument which will enable the nails to be cleaned efficiently by providing a measured, limited and accurately-controlled source of cleaning fluid.

Another object of the invention is to provide a leakproof container for a liquid cleaner in combination with an efficient means for cleaning the nails.

Another object of the invention is to provide a manicuring instrument containing cleaning fluid which may be easily and safely carried in the pocket, and used at any time as desired. Other objects and advantages will be apparent.

The invention is illustrated in the accompanying drawing, in which the figure is a longitudinal, medial section of an illustrative embodiment thereof.

Referring to the said drawing, 1 is the reservoir portion and handle of the fingernail cleaner having a filler cap 2 enclosing one end. The other end of the reservoir is partially closed by the annular ring 3 and is fully closed by the end piece 4 and frictionally held in place by being forced over the stepped annular shoulder 5 which is a part of the lower end of the reservoir 1.

The end piece 4 has running through its center and slidably therein a hollow tube 6 which has a blunt closed end at 7, and is pierced by minute orifices 8 at its lower extremity. Tube 6 has attached near to the lower end small bristles 9 which surround the minute orifices 8. At its upper end it is of sufficient diameter to make a snug fit in the orifice formed by the center of the annular ring 3. It also has an annular flange 10 which is of such diameter so that it snugly fits the sides of the end piece 4 at the upper straight section of the latter. Thus the end piece 4 and the flange 10 become a cylinder and a piston respectively. Between the annular ring 3 and the flange 10 is a coiled compression spring 11 which serves to keep the ring 3 and the flange 10

2

10 separated a predetermined distance, to form the chamber 12, while the flange 10 is prevented from being forced into the tapered portion of end piece 4 by the flange-stop 4a.

5 The tube 6 is provided with small orifices 13 at the bottom of the chamber formed between the ring 3 and the piston-flange 10. Tube 6 is also provided with an indented portion 14 which, when the spring 11 holds the ring 3 and the flange 10 apart, forms a channel 15 for the passage of liquid from the reservoir to the chamber 12. Tube 6 in the form shown has a tapered shape, after having a uniform diameter equal to the depth of the chamber 12. A non-tapering diameter is preferred here, because by the use of uniform diameter the tube 6 is held in alignment by the tip of the end piece 4 when the flange 10 is approaching the annular shoulder 5 and the said flange.

10 In operation the nail cleaner is filled with a soapy liquid or other type of cleaner by removing the cap 2 and filling the reservoir 1. When a user wishes to clean the nails the blunt end 7 of the tube 6 is placed against the end of the finger or some other resistant object and a slight push on the body of the instrument forces the piston flange 10 against the pressure of the spring 11. As the piston slides toward the annular ring 3, the notch 14 enters the reservoir chamber and, because of the snug fit of the top part of the tube 6 with the central orifice of the annular ring 3, the channel 15 is closed and the liquid in the chamber 12, which is now decreasing in size, is forced through the orifices 13, down the tube 6 and out through the minute orifices 8, which are preferably of capillary size, into the bristles 9. A suitable cap (not shown) may be applied to the tapering portion of 4 to cover and protect the brush and the end of the instrument.

15 When pressure is released on the point 7 the spring 11 returns the flange 10 to its rest position against the flange stop 4a, thus opening the channel 15 and allowing a new supply of liquid to enter the chamber 12 by gravity flow assisted by the suction occasioned by the partial vacuum created in the chamber 12 due to the decrease in volume of the liquid forced out of this chamber by the action of the piston flange when liquid is ejected through the orifices 13.

20 The instrument may now be rotated by the fingers under the user's nail thus effectively cleansing the nail by means of the brush and the cleansing fluid which has been extruded thereon.

25 The brush may be dried by rotating in a piece

of cloth or absorbent paper and will remain dry until further liquid is supplied to it, because the size of the orifices 8 is such that the cleansing liquid, which should be quite thin, will not pass therethrough except under pressure. In this dry condition it may be used for brushing and cleaning the nails without the aid of a detergent liquid. The liquid may be a thin soapy solution or a volatile fluid of the dry-cleaning order, and if the former the nails may be dried by the use of absorbent paper or cloth.

It will be understood that the frictional coaction between the tube 6 and its integral parts and the parts through which it passes is sufficient to prevent slipping when the instrument is rotated to cause rotation of the brush.

Various changes in the details of construction of the instrument shown and described and additions thereto may be made without departing from the scope of the invention. Thus the terminal 7 may be sharpened and/or extended if desired and used as a very effective cleaner to dislodge dirt or other foreign matter; and the improvements may be adapted for use with a dentifrice for cleaning the teeth instead of as a manicure instrument. The brush may be used dry or with moisture from the outside in either case.

What I claim is:

1. In a device of the character described, a hollow fluid containing handle, means for admitting a supply of fluid thereto, a diaphragm fixed therein substantially filling the bore thereof and having an aperture therein, a tubular member partly within the handle extending through said aperture and movable therethrough, said member having a recess therein at the part which extends through the said diaphragm opening and an opening spaced from the diaphragm and recess for the admission of fluid to the interior of said member, said member having a small outlet openings at an end which extends beyond the handle, said tube having radially extending bristles fixed thereto and said openings being insufficient in size to permit the fluid to escape therethrough except under pressure, a flange on said tubular member spaced from said diaphragm and filling the bore of the handle which is not filled by the said member and movable toward and from said diaphragm with said member forming a plunger to exert pressure on the fluid between it and said diaphragm after the recess has passed through the aperture, said tube having frictional engagement with said hollow handle preventing its free rotation therein.

2. In a device of the character described, a hollow fluid containing handle, means for admitting a supply of fluid thereto, a diaphragm fixed therein substantially filling the bore thereof and having a central aperture therein, a tubular member partly within the handle extending through said aperture and movable longitudinally therethrough, said member having a recess therein at the part which extends through the said diaphragm opening and an opening spaced from the diaphragm and recess for the admission of fluid to the interior of said member, said member having lateral small capillary outlet openings at an end which extends beyond the handle, said tube having radially extending bristles fixed thereto and said openings being insufficient in size to permit the fluid to escape therethrough by gravity, or such slight hydrostatic pressure as may be present, a flange on said tubular member spaced from said diaphragm and filling the bore of the handle which is not filled by the said member

and movable toward and from said diaphragm with said member forming a plunger to exert pressure on the fluid between it and said diaphragm after the recess has passed through the aperture, said tube having frictional engagement with said hollow handle preventing its free rotation therein.

3. In a device of the character described, a hollow fluid containing handle, means for admitting a supply of fluid thereto, a diaphragm fixed therein substantially filling the bore thereof and having an aperture therein, a tubular member partly within the handle extending through said aperture and movable therethrough, said member having a recess therein at the part which extends through the said diaphragm opening and an opening spaced from the diaphragm and recess for the admission of fluid to the interior of said member, said member having small outlet openings at an end which extends beyond the handle which end is otherwise closed, said tube having radially extending bristles fixed thereto and surrounding said openings and said openings being insufficient in size to permit the fluid to escape therethrough by gravity, a flange on said tubular member spaced from said diaphragm and filling the bore of the handle which is not filled by the said member and movable toward and from said diaphragm with said member forming a plunger to exert pressure on the fluid between it and said diaphragm after the recess has passed through the aperture and suction when moved in the opposite direction, said tube having frictional engagement with said hollow handle preventing its free rotation therein.

4. In a device of the character described, a hollow fluid containing handle, means for admitting a supply of fluid thereto, a diaphragm fixed therein substantially filling the bore thereof and having an aperture therein, a tubular member partly within the handle extending through said aperture and movable therethrough, said member having a recess therein at the part which extends through the said diaphragm opening and an opening spaced from the diaphragm and recess for the admission of fluid to the interior of said member, said member having small outlet openings at an end which extends beyond the handle, said tube having a brush affixed thereto and said openings being insufficient in size to permit the fluid to escape therethrough by gravity, a flange on said tubular member spaced from said diaphragm and filling the bore of the handle which is not filled by the said member and movable toward and from said diaphragm with said member forming a plunger to exert pressure on the fluid between it and said diaphragm after the recess has passed through the aperture and means for retracting said flange to and holding it in its normal position automatically and drawing a measured amount of fluid into the space between it and said diaphragm through adjacent openings, said tube and flange having frictional engagement with said hollow handle preventing its free rotation and other movement therein.

5. In a device of the character described, a hollow fluid containing handle, means for admitting a supply of fluid thereto, a diaphragm fixed therein substantially filling the bore thereof and having an aperture therein, a tubular member partly within the handle extending through said aperture and movable therethrough, said member having a recess therein at the part which extends through the said diaphragm opening and an opening spaced from the diaphragm and re-

cess for the admission of fluid to the interior of said member, said member having small outlet openings at an end which extends beyond the handle, said tube having radially extending bristles fixed thereto and said openings being insufficient in size to permit the fluid to escape therethrough by gravity, a flange on said tubular member spaced from said diaphragm and filling the bore of the handle which is not filled by the said member and movable toward and from said diaphragm with said member forming a plunger to exert pressure on the fluid between it and said diaphragm and expel it through said opening spaced from the diaphragm after the recess has passed through the aperture, said outlet openings adapted and arranged to discharge fluid radially between the bristles of the brush.

6. In a device of the character described, a hollow fluid containing handle, means for admitting a supply of fluid thereto, a diaphragm fixed therein substantially filling the bore thereof and having an aperture therein, a tubular member partly within the handle extending through said aperture and movable therethrough, said member having a recess therein at the part which extends through the said diaphragm opening and an opening spaced from the diaphragm and recess for the admission of fluid to the interior of said member, said member having small outlet openings in communication with the last named openings at an end which extends beyond the handle, said tube having radially extending bristles fixed thereto and said openings being insufficient in size to permit the fluid to escape therethrough by gravity, a flange on said tubular member spaced from said diaphragm and filling the bore of the handle which is not filled by the said member and movable toward and from said diaphragm with said member forming a plunger to exert pressure on the fluid between it and said diaphragm after the recess has passed through the aperture, said tube having frictional engagement with said hollow handle preventing its free rotation therein, said brush formed by the bristles being annular in form and rotatable with the handle and with said tube.

7. In a device of the character described, a hollow fluid containing handle, means for admitting a supply of fluid thereto, a diaphragm fixed therein substantially filling the bore thereof and having an aperture therein, a tubular member partly within the handle extending through said aperture and movable therethrough, said member having a recess therein at the part which extends through the said diaphragm opening and an opening spaced from the diaphragm and recess for the admission of fluid to the interior of said member, said member having small outlet openings at an end which extends beyond the handle, said tube having radially extending bristles fixed thereto and said openings being insufficient in size to permit the fluid to escape therethrough by gravity, a flange on said tubular member spaced from said diaphragm and filling the bore of the handle which is not filled by the said member and movable toward and from said diaphragm with said member forming a plunger to exert pressure on the fluid between it and said diaphragm after the recess has passed through the aperture, said tube having frictional engagement with said hollow handle preventing its free rotation therein, said tube having closed extremities.

8. In a device of the character described, a

hollow fluid containing handle, means for admitting a supply of fluid thereto, a diaphragm fixed therein substantially filling the bore thereof and having an aperture therein, a tubular member partly within the handle extending through said aperture and movable therethrough, said member having a recess therein at the part which extends through the said diaphragm opening and an opening spaced from the diaphragm and recess for the admission of fluid to the interior of said member, said member having small outlet openings at an end which extends beyond the handle, said tube having radially extending bristles fixed thereto and said openings being insufficient in size to permit the fluid to escape therethrough by gravity, a flange on said tubular member spaced from said diaphragm and filling the bore of the handle which is not filled by the said member and movable toward and from said diaphragm with said member forming a plunger to exert pressure on the fluid between it and said diaphragm after the recess has passed through the aperture, said tube having frictional engagement with said hollow handle preventing its free rotation therein, said tube having a closed pointed extremity beyond the bristles.

9. In a device of the character described, a hollow fluid containing handle, means for admitting a supply of fluid thereto, a diaphragm fixed therein substantially filling the bore thereof and having an aperture therein, a tubular member partly within the handle extending through said aperture and movable therethrough said member having a recess therein at the part which extends through the said diaphragm opening and an opening spaced from the diaphragm and recess for the admission of fluid to the interior of said member, said member having small outlet openings at an end which extends beyond the handle, said tube having radially extending bristles fixed thereto and said openings being insufficient in size to permit the fluid to escape therethrough by gravity, a flange in said tubular member spaced from said diaphragm, adjacent the opening which is spaced from the diaphragm and filling the bore of the handle which is not filled by the said member and movable toward and from said diaphragm with said member forming a plunger to exert pressure on the fluid between it and said diaphragm after the recess has passed through the aperture and means for retracting said flange to and holding it in its normal position automatically and drawing a measured amount of fluid into the space between it and said diaphragm, said tube and flange having frictional engagement with said hollow handle preventing its free rotation and other movement therein and said brush being normally dry and usable in that condition.
